(74) **Attorney, Agent, or Firm:** Michael Best &
Friedrich LLP

(57) **CLAIM**

We claim the ornamental design for a fastening nut, as
shown and described.

DESCRIPTION

FIG. 1 is a perspective view of a fastening nut according to
one embodiment.

FIG. 2 is a first side view of the fastening nut of FIG. 1.
FIG. 3 is a second side view of the fastening nut of FIG. 1.
FIG. 4 is a third side view of the fastening nut of FIG. 1.
FIG. 5 is a fourth side view of the fastening nut of FIG. 1.
FIG. 6 is a first end view of the fastening nut of FIG. 1; and,
FIG. 7 is a second end view of the fastening nut of FIG. 1.
Any portion of the fastening nut shown in broken lines is
included for the purpose of illustrating environment and
forms no part of the claimed design.
